UNITED STATES PATENT OFFICE

149,080

DESIGN FOR AN OVERHEAD COUNTER
DISPLAY STAND

Simon Malkin, New York, N. Y., assignor to United Cigar-Whelan Stores Corporation, a corporation of Delaware

Application November 29, 1946, Serial No. 135,181

Term of patent 14 years

(Cl. D80—9)

To all whom it may concern:

Be it known that I, Simon Malkin, a citizen of the United States and a resident of the city of New York, in the county of New York and State of New York, have invented a new, original, and ornamental Design for an Overhead Counter Display Stand, of which the following is a specification, reference being had to the accompanying drawing, constituting a part thereof, in which

Fig. 1 is a perspective view of an overhead counter display stand showing my new design;

Fig. 2 is an edge view of the stand shown in Fig. 1, taken in the plane 2—2 and in the direction indicated by the arrows;

Fig. 3 is an edge view of the stand taken in the plane 3—3, and in the direction indicated by the arrows;

Fig. 4 is a front elevational view;
Fig. 5 is a top plan view of the same.

I claim:

The ornamental design for an overhead counter display stand, as shown.

SIMON MALKIN.
